TIE FRAME

Ruth M. Kolkoski, East Grand Rapids, Mich.

Application December 7, 1949, Serial No. 131,575

4 Claims. (Cl. 223—65)

1

This invention relates in general to a new and improved form of tie frame for forming newly made ties, or for stretching and forming ties after they have been cleaned or washed.

It has been difficult heretofore in the making of ties, for example knitted ties made at home, to shape the ties properly after they were made. The regular so-called four-in-hand ties are customarily 48 inches to 51 inches or more in length. This means that a tie form or frame must be at least as long as the tie itself in order properly to shape the tie.

It is also customary for this type of tie to be made smaller intermediate the ends thereof throughout the length of that portion which extends around the neck of the wearer than at either end thereof. Thus, a tie form or frame for shaping the tie can not easily be inserted from one end thereof without unduly stretching the intermediate narrower portion.

Another disadvantage of a single length frame is the difficulty of carrying or transporting it because of the length thereof.

It is, therefore, one of the principal objects of the present invention to provide a tie frame made in sections which may be easily and quickly assembled for use and disassembled for convenience in carrying.

Another object of the invention is to provide a sectional tie frame which may be manufactured economically and which is designed to overcome all of the aforementioned disadvantages of tie frames heretofore used.

A further object of the invention is to provide a tie frame which may be formed of either metal, such as aluminum or steel, or a plastic, and which is made in sections easily assembled and disassembled.

Still another object of the invention is to provide a novel form of tie frame made in a plurality of interfitting sections so that the sections may be individually inserted within a tie and thereafter assembled together so that the total length of the sections will equal the over all length of the tie.

A still further object of the invention is to provide a tie form or frame which is formed in sections of a sufficiently resilient material so that it may be easily inserted and withdrawn from a tie.

Other objects and advantages of the invention will become apparent from reading the following description taken in conjunction with the accompanying drawing in which:

Fig. 1 is an elevational view of the tie frame with the sections thereof assembled;

2

Fig. 2 is an enlarged elevational view of one of the sections of the tie frame with the end section attached thereto;

Fig. 3 is an enlarged elevational view of the intermediate section of the tie frame;

Fig. 4 is an enlarged elevational view of the end section opposite to that of the end section shown in Fig. 2, and illustrating the tailpiece affixed thereto;

Fig. 5 is a longitudinal sectional view through one of the intermediate joints for joining two of the sections together; and

Fig. 6 is a longitudinal sectional view through one of the joints illustrating the manner in which one of the end sections is joined to the main section.

It is realized that frames have been provided heretofore for other articles of clothing such as trousers and socks. A tie frame, however,

presents problems and difficulties not present in these other articles because of the peculiar shape of the tie having an intermediate section of considerably narrower width than either of the end portions. It is, therefore, desirable to provide a tie frame which may be disassembled for ease in carrying and which may be attractively boxed and perhaps marketed with a kit having yarn therein for knitting a tie. The tie frame disclosed herein is intended primarily for use in stretching and shaping newly made knitted ties, but it will be clear that its usefulness may also extend to other types of ties which have been cleaned or washed. The frame can be used to stretch and form such ties for drying.

The tie frame of the present invention is formed preferably of three sections, such sections being two end sections and an intermediate section. The tip ends or tailpieces for the tie frame may be either formed integrally with the adjacent end section or may also be made to be assembled and disassembled therefrom in the same manner as the main sections of the frame.

Referring now more particularly to the drawing and especially to Fig. 1, it will be noted that the larger of the two end frames is indicated generally by the numeral 1, the intermediate section by the numeral 2, and the smaller end section by the numeral 3. The larger end section 1 has affixed thereto an end piece 4 formed by the downwardly diverging frame members 5 and 6. A hook 7 is preferably affixed to the end 4 whereby the entire tie frame may be suspended from a suitable support.

The larger end section 1 is composed of the side members 8 and 9 which converge from the

end member 4 toward the intermediate section 2. These side members are braced by a plurality of cross pieces 10, 11 and 12.

As stated before, the end 4 may be formed integral with the end section 1, or may be arranged to be disassembled therefrom. The intermediate section 2 is composed of the side members 13 and 14. These two side members 13 and 14 also converge at the same rate as the side members 8 and 9 of the end section 1 so that when the two sections are assembled, the side member 13 will form a continuation of the side member 8 in alignment therewith, and the side member 14 will form a continuation of the side member 9 in alignment therewith, as more clearly shown in Fig. 1.

These side members 13 and 14 of the intermediate section 2 continue to converge to a point beyond the center of a tie, as measured from the larger end thereof, and to a point indicated by the numeral 15 where a supporting cross member 16 connects the two side members together. An intermediate supporting cross member 17 is also provided to add to the rigidity of the frame. Beyond the point 15 the two side members 13 and 14 begin to diverge for a short distance.

The smaller end section 3 consists of side members 18 and 19 which diverge outwardly from the terminal portions of the side members 13 and 14 of the intermediate section 2. Again the side members 18 and 19 diverge at the same rate as the diverging portions of the side members 13 and 14 so that the corresponding side members of the two sections will be in alignment as shown in Fig. 1.

The side members 18 and 19 are connected by the supporting cross members 20 and 21 and are adapted to have mounted thereon or removably secured thereto the tailpiece 22. This tailpiece is formed by the downwardly converging side members 23 and 24 which conform substantially to the smaller pointed end of a four-in-hand tie. The side members of one section are arranged to telescope into recesses formed in the ends of the adjacent side members, thereby to provide removable connecting means between adjacent sections. The means preferably used for the removable connections between the sections are shown more clearly in Figs. 5 and 6.

Referring to Fig. 5, one of the side members such as that indicated by the numeral 13 is shown as being provided at the upper end thereof with an enlarged portion 25 having a recess 26 therein adapted to receive the lower end of a side member of the adjacent section such as the side 8. The other side 14 of the intermediate section also has a similar enlarged portion 27 to receive the lower end of the side member 9 of end section 1.

The opposite ends of the side members 13 and 14 of the intermediate section 2 are adapted to fit into similar recesses in the enlarged parts 28 and 29 on the inner ends of side members 18 and 19 on the other end section 3. Such removable connecting means between the adjacent sections enable them to be easily placed and held together frictionally while the tie is being shaped and yet will permit easy separation of the various sections during periods of time when the frame is not in use.

As stated previously the end pieces 4 and 22 may either be formed integrally with their respective end sections or may be removably attached thereto in a manner similar to that just

described with respect to the sections themselves. For example, the downwardly diverging sides 5 and 6 of the end piece 4 may have enlarged portions 30 and 31 to receive the upper ends of side members 8 and 9 of end section 1. Likewise the smaller end or tailpiece 22 may have enlarged portions 32 and 33 at the ends of the sides 23 and 24 to receive the lower ends of the sides 18 and 19 of the smaller end section 3. A detailed section of one of these connections is illustrated in Fig. 6 where the enlarged portion 32 is shown provided with a recess 34 to receive the lower end of the side member 18.

It will be noted that the sides of the assembled frame diverge outwardly at different rates from the point intermediate the ends of the frame where the sides begin to diverge. This enables the frame to conform closely to the shape of the average tie.

It is also to be noted that the supporting cross members such as 12, 16, 17 and 20 are preferably spaced inwardly a sufficient distance from the outer free ends of the respective sections to permit considerable flexing of those free ends to more easily enable these ends to be brought into alignment with the adjacent recessed enlarged portions for purposes of assembly.

The advantages residing in the frame of the present invention are many. The frame may be quickly and easily disassembled after use and requires very little space for storage when not in use. Likewise the space required for transporting the frame is relatively small. At least three sections are provided for the frame, all of which may be completely disconnected from each other. The means for connecting the sections together are such that the connection may be made easily when the various sections are all within the tie. When the frame is to be assembled for use within a tie, the intermediate section is first inserted because of the narrow neck portion intermediate the ends of the tie. The free ends of the intermediate section may be flexed sufficiently to enable them to be inserted within the narrow neck portion of the tie. The larger end section may then be inserted within the larger end of the tie and the free ends of the side members 8 and 9 may be inserted within the recess in the enlargements 25 and 27. The smaller end section 3 may then be inserted in the opposite end of the tie and the recesses in the enlargements 28 and 29 will receive the free ends of the side members 13 and 14. If the end pieces 4 and 22 are separate pieces, they may then be attached to the respective end sections. The hook 7 at one end of the frame may then be utilized to hang the frame with the tie thereon while it is being shaped.

Changes may be made in the form, construction and arrangement of parts from that disclosed herein without in any way departing from the spirit of the invention or sacrificing any of the attendant advantages thereof, provided, however, that such changes fall within the scope of the claims appended hereto.

The invention is hereby claimed as follows:

1. A tie form for shaping ties comprising a sectional frame including end and intermediate sections, said frame including side members diverging outwardly toward both outer ends thereof from a point intermediate said ends, a plurality of spaced cross members connecting the sides of each section, the smaller ends of said end sections being removably attached to the intermediate section adjacent thereto, and an end

piece at each end of the frame, said end pieces each having sides converging from the sides of the adjacent section toward each other and the sides of each end piece being connected together at the juncture thereof.

2. A tie form for shaping ties comprising a frame including two end sections and an intermediate section, said intermediate section having side members diverging outwardly toward both ends thereof from a point between the ends thereof, the rate of divergence of said side members from said point being greater toward one end than the other, one of said end sections having outwardly diverging sides and having interfitting engagement with the diverging sides of said intermediate section at one end thereof, and the other of said sections also having outwardly diverging sides and having interfitting engagement with the diverging sides of said intermediate section at the other end thereof, the sides of said end sections forming a continuation in a straight line of the sides of said intermediate section at each end thereof.

3. A tie form for shaping ties comprising a frame including two end sections and an intermediate section, said intermediate section having side members diverging outwardly toward both ends thereof from a point between the ends thereof and terminating in free end portions

capable of being flexed, each of said end sections adapted to be removably attached to the respective free end portions of said intermediate section, supporting cross members connecting the sides of each of said sections and spaced inwardly from the free ends thereof to permit flexing, and end pieces removably secured to the outer ends of said end sections.

4. A tie form for shaping ties comprising a frame including an intermediate section having spaced sides diverging outwardly toward both ends thereof from a point between the ends thereof and terminating in free end portions capable of being flexed, two end sections each adapted to be removably secured to the opposed free end portions of said intermediate section, and substantially triangularly shaped end pieces removably secured to the outer ends of said end sections.
